HAROLD P. GRAY, GEORGE W. JONES, AND HARVEY D. ROBERSON, OF LEOMINSTER, MASSACHUSETTS, ASSIGNORS TO WACHUSSETT SHIRT CO., OF LEOMINSTER, MASSACHUSETTS, A CORPORATION OF MASSACHUSETTS

COLLAR AND COLLAR STIFFENER

Application filed December 22, 1938. Serial No. 327,994.

This invention relates to soft collars and has particular reference to means for permanently stiffening the points of the collars.

Heretofore it has been usual to stiffen the points of a collar by inserting a piece of starched fabric between the outer and inner fabric portions of the collar. This method of stiffening is not entirely satisfactory, however, since it does not give sufficient stiffness, and the stiffness disappears and cannot be regained after the collar has been laundered.

It is an object of the present invention to provide a collar with point-stiffening means which is not affected by the laundering process or by the detergents used in laundering and which retains the points permanently stiff during the life of the collar.

A further object of the invention is the provision of a collar having a stiffener for the points thereof which is not liable to become frayed during the collar-manufacturing operations, or subsequently, which can be positioned readily between the fabric layers of the collar without catching on the fabric, and which can be sewed readily to the fabric of the collar and will not break between the stitches, is not deleteriously affected by the heat and pressure of ironing and will not crack in use.

A yet further object of the invention is the provision of a collar having its points stiffened by a cellulose-coated fabric stiffener which is inserted between and is attached to the fabric layers of the collar.

Another object of the invention is the provision of a stiffener for the point of a collar composed of a sheet of fibrous material, as a suitable fabric, which is coated on one and preferably both sides, or impregnated, with a stiffening film of water-insoluble colloidal material as nitro-cellulose.

A further object is generally to improve upon collars and stiffeners therefor.

Fig. 1 is a plan view of a collar embodying the present invention turned up from the attached band.

Fig. 2 is a detail of the construction of the collar at a point thereof and illustrating the manner of uniting the outer and inner plies

of the collar by the edge seams, prior to the turning of the collar.

Fig. 3 is a view similar to Fig. 1 but showing in dotted lines the position of the stiffeners in the points of the collar.

Fig. 4 is a detail view of one of the points of the collar with one of the fabric plies removed to expose the stiffener.

Fig. 5 is a plan view of the stiffener comprising part of the present invention.

Fig. 6 is a section taken along line 6-6 of Fig. 3.

Fig. 7 is an enlarged section of the stiffener taken along line 7-7 of Fig. 5.

The collar here shown for purposes of illustration is attached to a shirt but the invention can be applied equally well to a detached collar.

The collar 10 is composed of two plies or layers 10a and 10b of fabric with or without the usual linings 10c which are united at the edge by a line of edge stitching 12 as shown in Fig. 2. The attached fabric layers are then turned inside out in the usual manner to locate the line of edge stitching at the outside edge of the collar. The fabric layers are free at their inner edges and these edges are interposed between the outer and inner fabric layers of the band 14 and are attached together and to the band by a line of stitching 16. The collar is shaped to provide points 18 which, in accordance with this invention, are provided with stiffening means.

In accordance with this invention the stiffener 20, see Figs. 4 through 7, consists of a fibrous, as a fabric, body 20a which has a more or less triangular configuration to conform with the outline of the collar point. The fabric is stiffened to the required degree by treating it with a stiffening agent which preferably is composed of a cellulose ester as a nitro-cellulose such as pyroxyline or celluloid. Preferably, the fabric is coated on both sides with a solution of nitro-cellulose in a volatile solvent which, when the solvent has evaporated, leaves the solid films or layers 20b on opposite faces of the fabric. If desired, the fabric can be impregnated with the stiffening solution although in practice it is found that the coating of the fabric on oppo-

site sides gives excellent results. The coating solution is relatively thin and fluid so that it penetrates the fabric to a considerable degree and is adherent to the strands and fibres of the fabric body. The nitro-cellulose films impart the desired degree of stiffness to the stiffener and the degree of stiffness can be varied by varying the thickness of the films, either by regulating the amount of solution spread onto the fabric or by varying the proportion of nitro-cellulose in the coating solution.

The stiffener is inserted in the point of the collar, between the outer and inner fabric layers 10a and 10b thereof in the position shown in Fig. 3. The usual top line of stitching 22 is then sewed into the collar around the margin thereof and through the fabric layers and also through the stiffener, thus uniting the stiffener permanently in place in the point of the collar. The collar is then inserted between the usual outer and inner plies of the band and is attached thereto by the line of stitching 16, which also passes through one end of the stiffener. The completed collar may be ironed under pressure to straighten the stiffener, the heat of ironing softening the thin stiffening films so that the ironing pressure can straighten them, if warped; and the films when cool will retain their straightened form.

The stiffener constructed and applied as above described is highly satisfactory. It imparts the required degree of stiffness to the point of the collar and yet is flexible. The stiffness is not deleteriously effected by water or by the ordinary detergents used in laundering or by the heat and pressure of ironing and thus preserves its stiffness throughout the life of the collar. The stiffening films do not crack on flexing due to their thinness and to the reinforcements provided by the fabric 20a. The stiffener will not break at the line of stitching 22 since the fabric fibres bond together the film sheets on both sides of the stitching. The stiffener can be inserted easily into the point of the collar since the edges of the stiffener are smooth and free from sharp projecting parts which might catch on the fabric of the collar. The fabric sheet 20a cannot fray because the films 20b hold the edge strands of the fabric sheet in place. The stiffener cannot readily curl because both sides of the fabric body 20a have a film adherently attached thereto. If the stiffener becomes warped in washing the heat and pressure of ironing softens the films sufficiently to straighten them.

With the usual starched stiffener it has been necessary to secure the body of the stiffener to the collar by means additional to the lines of stitching 22 and 16 to prevent the stiffener from curling when in use. The present stiffener will not curl so that the regular lines of stitching 22 alone are suf-

ficient to hold it in place without further means. The present stiffener thus reduces sensibly the labor of building the collar.

It has been proposed heretofore to stiffen the points of the collar either by sewing stiff pieces of fabric, as haircloth, to one or both plies of the collar, or by building pockets in the collar adapted removably to receive stiff stiffening strips as sheet celluloid. The present collar, in addition to the advantages above set forth, can be made much cheaper than such collars and is free from the defects of such collars.

While the stiffening or film-forming material of the stiffener has herein been specifically described as a nitro-cellulose, it can as well be another cellulose ester as cellulose acetate, or other material capable of giving equally good results when used as above described.

We claim:

1. A soft collar which at the point thereof is composed of outer and inner plies and has a point-stiffener consisting of a cellulose-coated fabric body which is interposed between said fabric plies and which is sewed to said plies by a line of top stitching which follows the free edge of the collar and passes through two of the edge-portions of the stiffener, and a second line of stitching which secures another edge of the stiffener to said plies.

2. A soft collar consisting at its point of outer and inner fabric layers, and a point stiffener which is interposed between and is attached only at the edge thereof to said fabric layers at the point only of the collar the collar elsewhere being free from the stiffener, said point stiffener consisting of a fibrous body containing a flexible water-insoluble stiffening agent which is adherently united with the fibres of said fibrous body.

3. A soft collar containing at the point only thereof a stiffener consisting of a textile body having adherent to both sides thereof flexible sheets of water-insoluble stiffening material in colloidal form.

4. A soft collar containing therein at the point thereof a stiffener consisting of a textile body having adherent to both sides thereof flexible sheets of celluloid.

5. A soft collar containing between the outer and inner fabric plies thereof at the point a point-stiffener consisting of a cellulose-coated fabric body which is stitched to both plies of the collar.

6. A soft collar containing therein at the point thereof a stiffener composed of a fibrous sheet containing a stiffening agent which retains its stiffness permanently and is insensitive to water and to laundering detergents, and is free from cracking when flexed.

7. A soft collar consisting of outer and inner fabric layers, and a point stiffener interposed between and attached only at the edge thereof to said fabric layers at the point

only of the collar, the collar elsewhere being free from said point stiffener, said point stiffener consisting of a flexible fibrous body which is coated with a water-insoluble cellulose ester which constitutes a stiffening agent for said flexible body.

In testimony whereof, we have signed our names to this specification.
